UNITED STATES PATENT OFFICE.

CHARLES EVERETT COLGROVE, OF TORONTO, ONTARIO, CANADA.

PAPERBOARD-CUTTING MACHINE.

Application filed January 10, 1927. Serial No. 160,176.

This invention relates to a paper board cutting machine as described in the present specification and illustrated in the accompanying drawings which form part of the 5 same.

The invention consists essentially of the novel features pointed out broadly and specifically in the claims for novelty following an explanation in detail of an acceptable 10 form of the invention.

The objects of the invention are to build a paper board cutting machine wherein the knives while cutting, travel with the board; to prevent buckling of the board while being cut; to so design the upper knife-operating 15 mechanism, that the speed of the knives will be slightly increased immediately following their engagement with the paper stock; to have means of easily setting the 20 machine for the different lengths of cut required; and generally, to manufacture an efficient and improved paper board cutting machine capable of accomplishing the afore- 25 said objects.

In the drawings, Figure 1 is a side elevation view;

Figure 2 is a plan view;

Figure 3 is a sectional view taken on line 3-3 in Figure 2, showing parts broken 30 away;

Figure 4 is a sectional view taken on line 4-4 in Figure 2;

Figure 5 is a fragmentary plan view;

Figure 6 is a part elevation and part sec- 35 tion view of the shaft 74, sleeve 72, etc.

Figure 7 is a perspective view of the cam;

Figure 8 is a perspective view of the lever 27;

Figure 9 is a fragmentary perspective 40 view;

Figure 10 is a section view of the gear 11.

Like numerals of reference indicate corresponding parts in the various figures.

Referring to the drawings, 10 are two spaced upright standards forming with the standards 10^A, the base or frame of the machine.

11 is a horizontally-arranged bevel gear 50 rotating in the bearing 12 carried by the two transverse channels 13; the channels are secured at their ends to the standards 10.

14 is a shaft suitably journaled in one of the standards 10 and rigidly mounting the 55 bevel gear 16 meshing with the gear 11.

The gear 11 is therefore actuated by the rotation of the shaft 14.

18 is a table or carriage formed of the cross members 17 and 19, and of the longitudinal members 20 sliding in the grooves 60 or trackways 21 formed in both of the standards 10. Pivotal secured to the rear part of the table 18, is a U-shaped frame 23 carrying the knife 24 positioned to co-act with the corresponding knife 25 carried by the front end of the table 18. 27 are levers 65 pivotally mounted to the front end of said table and each having a roller 28 riding in a groove or track 29 formed in the inner face of said standards 10; 30 is a link pivotally mounted between each side member of the U-frame 23 and each of the levers 27. The grooves 29 are deepened or enlarged as at 28, to present substantially an inverted isosceles triangle within which is pivotally 70 mounted a substantially triangularly-formed cam 31 having the crank end 31^A; the cam is normally held in the position shown in Figure 4 by means of the tensioned spring 32. It will be seen that as the table 18 moves from rear to front (left to right in Figure 1), the rollers 28 will engage the edge 33 of the cams, cause the levers 27 and the U-frame to be swung downwardly, and therefore bring the knives into co-action; 75 as the rollers ride upon the edge 34 of the cams, these will be rotated to the position shown in Figure 9; when the table has moved sufficiently to cause the rollers to clear the cams, the tensioned springs 32 will tilt or rotate the cams back to the position shown in Figure 4; as the table moves from front to rear (right to left in Figure 1), the rollers will engage and ride over the edge 37 of the cams, the table travelling back to 80 the position shown in Figures 1 and 4 without actuating the knife 24 downwardly.

The cams 31 are preferably so located or the effective length of the levers 27 made such, that when the knife 24 engages the paper stock, the pin 36^A will be slightly in advance of a line drawn at right angles to the longitudinal axis of the machine and passing through the centre of the gear 11.

35 is a block sliding between the cross members 19 of the table 18, and 36 is a second block pivoting on the pin 36^A and sliding in the slide bearings 42 which are rigidly carried by the gear 11. 38 is a bearing 105 rigidly mounted on the upper face of the 110

gear 11 and rotatably and non-slidably mounting the shaft 39 which is threaded to threadingly engage the block 36; 41 is a bevel gear rigidly carried by the shaft 39.

6 By rotating the gear 41, the shaft 39 is rotated, shifting the block 36 in the axis of said shaft and therefore shifting the block 35 in the axis of the bars 19.

43 is the drive shaft, suitably journaled 10 in the standards 10^A, and mounting the drive pulley 44. As the drive shaft is driven at constant speed and the length of the cut

depends upon the speed of the bevel gear 11, suitable means of varying the speed of 15 the shaft 14 must be provided; accordingly, I use a well known speed cone mechanism having the usual cones 45 and pivoted levers 46, and belt 47.

48 are two blocks pivotally carried by the 20 levers 46 and threaded to receive the threaded spindle 49 which rotates in the standards 10, the spindle being threaded with right-hand and left-hand threads; 51 are two gears rigid with the sleeve 52 which is slidably and non-rotatably mounted on the

25 spindle 49; 57 is a gear rigidly mounted on the shaft 58 rotating in the bearing 60 and formed to engage with either of the gears 51; 59 is a bevel gear rigidly carried by the 30 shaft 58 and meshing with the gear 61 rigidly carried by the shaft 14; the gear 57 is therefore rotated from the rotation of the shaft 14, and the spindle 49 can be rotated to shift the levers 46 toward or away from 35 one another and therefore vary the speed of the belt 47.

To one end of the spindle 49 is rigidly mounted a bevel gear 62 meshing with the bevel gear 63 which is rigidly carried by 40 the spindle 64; the spindle rotates in a suitable bearing 65 and has one end threaded to engage the threaded block 66; the block carries a stud slidably engaging the slotted hand 67 pivotally mounted on the front face 45 of the graduated dial plate 68. As the shaft 49 rotates, therefore, the gears 62 and 63 and spindle 64 are rotated, the block 66 shifted, and the hand 67 operated.

69 is a vertically-arranged rotatable shaft 50 rigidly mounting at the top the bevel gear 70 meshing with the gear 41, and rigidly mounting at the bottom the bevel gear 71; 74 is a horizontally-arranged shaft rotating in the bearings 75 carried by the underside 55 of the channels 18; the shaft rigidly carries the sprocket wheel 76 and slidably and non-rotatably carries the bevel gear 77 formed to engage with the gear 71; 72 is a sleeve 60 slidably and rotatably carried by the shaft 74 and having the bevel gear 73 formed to engage with the gear 71; 81 is a sprocket wheel rigidly carried by the sleeve 72. It will be seen that the shaft 74 and sleeve 72 can be rotated independently of one another.

82 is a rod sliding at one end in one of the standards 10 and at the other end in the bearing 60, and having jaws 83 rotatably engaging the groove 84 formed in the gear 77 and sleeves 72 and 52. The sleeve 72 and gear 77 are so positioned upon the shaft 74 that the gear 73 is clear of the gear 71 when the gear 77 engages the gear 71, and vice versa; similarly, the sleeve 52 is so positioned upon the spindle 49 that only one of the gears 51 is in engagement at one time with the gear 57.

85 and 86 are sprocket wheels rigidly carried by the spindle 49, and 87 and 88 are sprocket chains operatively connecting the 80 sprockets 85 and 86 to the sprockets 76 and 81, respectively.

The rod 82 is pivotally connected at one end to the control lever 89 which is provided with a suitable clamping mechanism 95, whereby the lever is releasably locked in three positions; one extreme position determining that at which the engagement of the gears 73 and one of the gears 51 is effected with the gears 71 and 57, respectively; the other extreme position determining that at which the engagement of the gear 77 and the other of the gears 51 is effected with the gears 71 and 57, respectively; and the intermediate or neutral position determining 95 that at which the gears 71 and 57 are free of their co-acting gears.

Therefore, when the control lever is in its neutral position, the spindle 49 does not rotate; when the lever is in one of its extreme positions, the spindle is rotated to either increase or decrease the speed of the belt 47; if the speed of the belt is increased, the number of revolutions per minute of the gear 11 is increased, the number of cuts per minute correspondingly increased, and since the paper stock is fed at constant speed, the length of cut is decreased; similarly, if the speed of the belt is decreased, the number of cuts per minute is decreased and the length of cut correspondingly increased.

In order to prevent buckling or pulling, the speed of the knives when cutting must be made substantially equal to that of the stock; and if the table is to travel faster than the stock immediately after being engaged by the knives, the longitudinal component of the lineal velocity of the pin 36^A must be equal to the speed of the stock at the instant the knives engage the stock. Since the speed of the knives is equal to the longitudinal component of the lineal speed of the pin 36^A and its speed varies directly with its distance from the centre of the gear 11, it follows that as the speed of the gear 11 is decreased, the distance of the pin 36^A from the centre of said gear must be proportionately increased; and similarly, as the speed of said gear is increased the distance between said pin and the centre of said gear must be 130

proportionately decreased. Therefore, the ratio of the various co-acting gears co-ordinating the shifting of the pin 36^A with the rotation of the spindle 49 must be such that the longitudinal component of the lineal velocity of the pin 36^A is approximately equal to the velocity of the paper at cutting time.

As the shifting of the block 36 and pin 36^A is effected by the rotation of the shaft 39 and gear 41 and the gear 41 is mounted on the rotating gear 11, it follows that the gear 41 must be rotated faster in one direction than in the other if the rate at which the block 36 is shifted in each direction is to be proportionate to the speed of the spindle 49; accordingly, the sprocket 85 is made larger in diameter than the sprocket 86.

90 are the feed rollers, the lower roller 20 having the sprockets 91 driven from the sprockets 92 through the chains 93.

95 is a removable plate carried by the table 18, its upper face being substantially flush with the edge of the knife 25, as best shown 25 in Figure 4.

Operation.—The drive shaft, which rotates at constant speed, feeds the stock uniformly through or between the rollers 90. The control lever is actuated forwardly or 30 rearwardly to cause the spindle 49 to be rotated one way or the other, and the lever held or clamped until the hand 67 travels to indicate the length of cut desired, after which it is brought to neutral position.

35 As the gear 11 rotates, the block 35 is carried therewith while sliding back and forth between the bars 19, the table 18 travelling back and forth in the grooves 21. As the table travels, the rollers ride in the 40 grooves 29; as the rollers engage the cams 31, the U-frame is swung or oscillated downwardly and upwardly according as to whether the rollers engage the edge 33 or 34 of said cams; when the rollers engage the 45 edge 37 of said cams, the frame remains in a substantially fixed plane.

What I claim is:

1. In a paper stock cutting machine, a reciprocating table carrying a knife therewith, an oscillating member carried by said table and having a knife positioned to co-act with said first-mentioned knife, means for feeding the paper stock between said knives, and means adapted for oscillating said member from said table in its movement.

2. In a paper stock cutting machine, a reciprocating table carrying a knife therewith, an oscillating member carried by said table and having a knife positioned to co-act with said first-mentioned knife when said member is swung downwardly, means for feeding the paper stock between said knives, and a cam mechanism adapted for oscillating said member from said table in its movement.

3. In a paper stock cutting machine, a frame, a drive shaft, a reciprocating table carrying a knife therewith, an oscillating member carried by said table and having a knife positioned to co-act with said first-mentioned knife, means for feeding the paper stock between said knives at constant speed, a gear rotatably mounted under said table, means operatively connected between said gear and table for actuating same from the rotation of said gear, means for actuating said gear from the rotation of said drive shaft, and means for varying the speed of said gear.

4. In a paper stock cutting machine, a reciprocating table carrying a knife therewith, an oscillating member carried by said table and having a knife positioned to co-act with said first-mentioned knife, means for feeding the paper stock between said knives at constant speed, means for varying the number of strokes per minute of said table, and indicating means operatively connected with said last-mentioned means for determining the length of cut required.

5. In a paper stock cutting machine, a reciprocating table carrying a knife therewith, an oscillating member carried by said table and having a knife positioned to co-act with said first-mentioned knife, means for feeding the paper stock between said knives at constant speed, means for varying the number of strokes per minute of said table, and means operatively connected with said last-mentioned means adapted for automatically adjusting the speed of said table when the knives are cutting to the speed of the stock.

6. In a paper stock cutting machine, a frame, a drive shaft, a table slidably mounted in said frame and having a transverse slot, a knife carried by said table, an oscillating member carried by said table and having a knife positioned to co-act with said first-mentioned knife, means for feeding the paper stock between said knives at constant speed, a gear rotatably mounted under said table, means for actuating said gear from said drive shaft, means for varying the speed of said gear, and a block pivotally carried by said gear at a point distanced from the centre thereof and slidably engaging the slot in said table.

7. In a paper stock cutting machine, a reciprocating table carrying a lower knife therewith, an oscillating member carried by said table and having an upper knife positioned to co-act with said lower knife, means for feeding the paper stock between said knives at constant speed, and means for bringing the upper knife in engagement with the paper stock slightly before said table has completed the first half of its forward stroke.

8. In a paper stock cutting machine, a frame, a drive shaft, a table slidably mount-

- ed in said frame and having a transverse slot, a knife carried by said table, an oscillating member carried by said table and having a knife positioned to co-act with said first-mentioned knife, means for feeding the paper stock between said knives at constant speed, a gear rotatably mounted under said table, means for actuating said gear from said drive shaft, means for varying the speed 5 of said gear, a block pivotally carried by said gear at a point distanced from the centre thereof and slidably engaging the slot in said table, and means for varying the distance between said block and the centre of 10 said gear automatically with the varying of the speed of said gear.
9. In a paper stock cutting machine, a frame, a drive shaft, a table slidably mounted in said frame and having a transverse 20 slot, a knife carried by said table, an oscillating member carried by said table and having a knife positioned to co-act with said first-mentioned knife, means for feeding the paper stock between said knives at constant speed, a gear rotatably mounted under said table, means for actuating said gear from said drive shaft, means for varying the speed 25 of said gear, a spindle rotatably and non-slidably mounted upon said gear, a block 30 slidably mounted in the axis of said spindle and threaded to engage one end thereof, a
- second block sliding in the slot in said table and pivotally connected to said first-mentioned block, and means for rotating said spindle automatically with the varying of 35 the speed of said gear.
10. In a paper stock cutting machine, a frame, a gear-actuated reciprocating table carrying a knife therewith, a member pivotally carried by said table and having a knife 40 positioned to co-act with said first-mentioned knife, means for feeding the paper stock between said knives at constant speed, and a cam mechanism adapted to swing said member downwardly and upwardly on the forward stroke of said table.
11. In a paper stock cutting machine, a frame, a table carrying a knife therewith, a frame pivotally carried adjacently of the rear end of said table and having a knife 45 positioned to co-act with said first-mentioned knife, a track in said frame, a pair of levers pivoting adjacently of the front end of said table and having each a roller riding in said track, a link pivotally connected between said 50 frame and said levers, and cams positioned in the path of said rollers and adapted to swing said levers downwardly and upwardly on the forward stroke of said table.

Signed at the city of Toronto, this 28th 60
day of December, 1926.
CHARLES EVERETT COLGROVE.
